SEWING MACHINE WITH INTERMITTENT SHIRRING ATTACHMENT

Arthur L. Plamondon, Kenneth H. Wakefield, and
Walter A. Plamondon, Auburndale, Mass.

Application May 19, 1949, Serial No. 94,128

6 Claims. (Cl. 112—132)

1

This invention relates to sewing machines, and more especially to high speed machines having intermittent shirring attachments, although it is capable of more general application.

It has been found in practice that occasions arise when it is highly desirable to remove the separating blade of a shirring attachment to a position far distant from its operative or shirring position below the under side of the presser foot, as for instance when a closed sleeve is to be sewed to a gown.

It is, therefore, one of the objects of our invention to pivotally attach the separating blade to a support block capable of swinging movement in a horizontal plane of about 180° in order that the blade will not interfere with the operation of the machine for purposes other than shirring.

Other objects are to simplify the construction, reduce the cost, and increase the efficiency of intermittent shirring attachments of sewing machines.

One embodiment of our invention that has given good results in practice is shown in the accompanying drawings in which

Fig. 1 is a front elevation of an overseaming sewing machine of the Merrow type that embodies our invention.

Fig. 2 is a left side elevation of the machine shown in Fig. 1.

Fig. 3 is a side view of the lever that governs the intermittent shirring mechanism attached to its support.

Fig. 4 is an end view of said lever and its support.

Fig. 5 is a side view of the governing lever.

Fig. 6 is a plan view of the presser foot.

Fig. 7 is a side elevation of the presser foot.

Fig. 8 is a plan view of the separating blade holder block with said blade attached.

Fig. 9 is a side view of said block and blade.

In the particular drawings selected for disclosing our invention and the underlying principle thereof, said drawings to be considered as illustrative only and not restrictive, 10 is the base of the well known Merrow overseaming machine to which, for purposes of illustration only, our improved intermittent shirring attachment is applied. Secured to said base are the several elements of an overseam machine, which, being well understood by those skilled in the art, require no detailed description herein.

The inner end of the separating-blade holder-block 11 is pivotally mounted by the stud 12 for swinging movement through an arc of about 180° to the bracket 13 which is secured to the frame

2

cap 14 by the screws 15. Attached to said block by the screw 16 is an arm 17 through the outer end of which is threaded an adjusting screw 18 operable by the knurled head 19 to force the free end thereof against the resilient separating blade 20 secured by the screws 21 to the ledge 22 of said block for the purpose of bringing the outer end 22' of said blade 20 (Figs. 2 and 8) into shirring position for a continuous shirring operation.

In the present instance the shirring is accomplished by the well known differential feed-dog method, the feed-dogs being indicated 23, 24, of which the rear dog travels at a lower speed than the forward dog 23.

For intermittent shirring, the position of the separating blade is governed by the lever 25 (Figs. 1 and 3) pivoted by the screw 26 in the bifurcated upper end of the support member 27 which is mounted on the machine frame for vertical adjustment by the screws 28, 29 disposed in the slots 30, 31, respectively. A compression spring 32 normally maintains the lever in its uppermost position against the stop afforded by the screw 32'. The lever 25 may be connected to a foot pedal (not shown) by a chain (not shown) passing through the hole 33 in said lever. Secured to the underside of the separating blade by the screw 34 and bolt 35 is a horizontally disposed U-shaped member 36, the lower leg 37 of which is located for cooperation with the free end of the lever 25 when the latter is depressed, thereby placing the free end of the separating blade into shirring position.

35 The presser foot 40 is pivoted to the presser-foot yoke 41 by the screw 42 passing through the latter and the bifurcated inner end of the presser foot. By the bar 43 controlled by the spring retracted latch 44, the presser foot, notched as 40 shown at 45 to receive said bar, is maintained in operative position. The free end 40' of the presser foot is given a pronounced upward curvature which terminates in a flat portion 40'' from which rises an arm 40''' substantially perpendicular thereto. The curved free end of the presser foot forms with the separating blade disposed beneath it a wide open mouth to receive the fabric to be stitched or the fabric to which the shirred material is to be sewed.

50 The machine is a three-thread machine, having one needle thread and two looper threads. A portion of the curved needle is indicated at 46. A portion of the needle thread take up appears at 47. The work plate 48 is pivoted at 49 to a support 50 near the back of the frame. The

two-blade cutter mechanism is indicated at 51, the differential feed-dog arrangement at 52, and the main shaft at 53.

While the machine has been particularly described, it is to be understood that our invention is not limited to use in connection therewith.

Operation: The parts being in the positions shown in Figs. 1 and 2, fabric to be shirred is placed on the work plate and drawn through the space between the feed-dogs and the separating blade, and the goods to which the shirred fabric is to be sewed is passed into the space between said blade and the presser foot. The engaging lever 25 is depressed thereby forcing the free end of the separating blade downwardly to press said fabric against the feed-dogs. The fabric will be shirred and simultaneously sewed to said goods until the engaging lever is released.

For continuous shirring, the separating blade is held down by turning the screw 18 against the same. It will be noted that the separating-blade holder-block comprises three sections of progressively diminishing heights or thicknesses, viz., the right hand section which supports the arm 17 and spaces the screw 18 when in inoperative position away from the blade, the intermediate section 22 which carries the blade and the left hand section 21' spaced away from the blade in order to permit the screw 18 to force the blade, which is of steel or other resilient material, downwardly part way into the space between the blade and said left hand section.

When the machine is to be used for stitching or overseaming the separating-blade holder-block is swung through an arc of about 180° and rests against the right hand side of the frame as indicated in dotted lines in Fig. 1. This has been found to be a great convenience in all kinds of work that does not involve shirring.

Having thus described an illustrative embodiment of our invention without, however, limiting ourselves thereto, what we claim and desire to secure by Letters Patent is:

1. In a sewing machine having a frame cap, a shirring attachment comprising a bracket secured to said frame cap, a separating-blade holder-block, means pivoting said holder-block to said bracket for swinging movement in a horizontal plane, shirring mechanism attached to said machine, and a separating blade secured to said holder-block, said blade being disposed for cooperation with said mechanism when said holder-block is in one position and for non-cooperation therewith when said holder-block is in another position.

2. In a sewing machine having a frame cap, a shirring attachment comprising a bracket secured to said frame cap, a separating-blade holder-block, a presser foot, means pivoting said holder-block to said bracket for swinging movement in a horizontal plane, shirring mechanism attached to said machine, and a separating blade secured to said holder-block, said blade being disposed to rest lightly against the under side

of said presser foot when said holder-block is in one position and to be far removed therefrom when said holder-block is swung approximately one hundred and eighty degrees away from the position first mentioned.

3. In a sewing machine having a frame cap, a shirring attachment comprising a bracket secured to said frame cap, a separating-blade holder-block, said holder-block being formed in three sections of progressively diminishing thicknesses, pivoting means passing through the inner end of the thickest section of said holder-block and said bracket, an arm secured to said thickest section and overlying the other two sections, a separating blade of resilient material secured to the intermediate section of said holder-block, screw means threaded to said arm near the outer end thereof for engagement with said blade and the third or thinnest section of said support underlying said blade at the point of engagement of said screw means with said blade.

4. In a sewing machine having a frame cap, a shirring attachment comprising a bracket secured to said frame cap, a separating-blade holder-block, means pivoting said holder block to said frame cap, a separating blade secured to said holder block, a U-shaped member secured to the under side of said blade at a point intermediate the ends thereof and spring retracted lever means for engaging said member at will for depressing said blade.

5. In a sewing machine having a frame cap, a shirring attachment comprising a bracket secured to said frame cap, a separating-blade holder-block, pivotally connected to said bracket for swinging movement of substantially one hundred and eighty degrees in a horizontal plane, a separating blade secured to said holder-block intermediate the ends thereof, means attached to said holder-block for depressing said blade for continuous shirring, and means carried by said blade for cooperation with means for depressing said blade at will for intermittent shirring.

6. In a sewing machine having a frame cap, a shirring attachment comprising a bracket secured to said frame cap, a separating-blade holder-block, a presser foot, means pivoting said holder-block to said bracket for swinging movement in a horizontal plane, shirring mechanism attached to said machine, and a separating blade secured to said holder-block, said blade being disposed to rest lightly against the under side of said presser foot when said holder-block is in one position and to be far removed therefrom when said holder-block is swung approximately one hundred and eighty degrees away from the position first mentioned, said presser foot having an upwardly curved end to form with said blade a wide open mouth to receive the fabric to be stitched.
